UNITED STATES PATENT OFFICE

149,026

DESIGN FOR AN ELECTRIC LIGHTING FIXTURE

Martin W. Schwartz and Max J. Marks,
Chicago, Ill.

Application July 1, 1946, Serial No. 131,244

Term of patent 14 years

(Cl. D48—4)

To all whom it may concern:

Be it known that we, Martin W. Schwartz and Max J. Marks, citizens of the United States and residents of Chicago, in the county of Cook and State of Illinois, have invented a new, original, and ornamental Design for an Electric Lighting Fixture, of which the following is a specification, reference being had to the accompanying drawing, forming a part thereof.

In the drawing,

Figure 1 is a perspective view of an electric lighting fixture showing our new design as taken from the under side thereof;

Figure 2 is an end view of the fixture; and

Figure 3 is a cross sectional view of the fix-

ture taken along the transverse mid-section of Fig. 1.

We claim:

The ornamental design for an electric lighting fixture, as shown.

MARTIN W. SCHWARTZ.
MAX J. MARKS.
